(57) **CLAIM**

The ornamental design for a dual remote control holder, as shown and described.

DESCRIPTION

FIG. 1 is a top perspective view showing the top, rear, and left side of the dual remote control holder in an closed position;

FIG. 2 is a left side elevational view thereof in an closed position;

FIG. 3 is a right side elevational view thereof in an closed position;

FIG. 4 is a top plan view thereof in an closed position;

FIG. 5 is a bottom plan view thereof in an closed position;

FIG. 6 is a rear elevational view thereof in a closed position;

FIG. 7 is a front elevational view thereof in a closed position; and,

FIG. 8 is a perspective view of the invention in a partially open position.

The broken lines shown in FIGS. 1-8 are for illustrative purposes only and form no part of the claimed design.
